UNITED STATES PATENT OFFICE

126,537

DESIGN FOR A COMBINED PROPELLER SHAFT STRUT AND REVERSING RUDDER

Andrew J. Higgins, New Orleans, La., assignor to
Higgins Industries, Inc., New Orleans, La., a
corporation of Louisiana

Application October 11, 1939, Serial No. 87,627

Term of patent 14 years

To all whom it may concern:

Be it known that I, Andrew J. Higgins, a citizen of the United States, residing at New Orleans, in the parish of Orleans, and State of Louisiana, have invented a new, original, and ornamental Design for Combined Propeller Shaft Strut and Reversing Rudder, of which the following is a specification, reference being had to the accompanying drawing, forming part thereof.

In the drawing:

Figure 1 is a side elevational view of a com-

bined propeller shaft strut and reversing rudder, showing my new design; and

Figure 2 is a perspective view.

The dominant feature of the design resides in the shape of the reversing rudder and its relation to and association with the strut, bearing plate and skeg, all as shown.

I claim:

The ornamental design for a combined propeller shaft strut and reversing rudder, as shown and described.

ANDREW J. HIGGINS.
